Patented Aug. 17, 1920.

UNITED STATES PATENT OFFICE.

JOHN KASPAR AND RUD F. BERAN, OF MOULTON, TEXAS.

WATER-LEVEL.

1,349,613.

Specification of Letters Patent. Patented Aug. 17, 1920.

Application filed November 6, 1918. Serial No. 129,851.

To all whom it may concern:

Be it known that we, JOHN KASPAR and RUD F. BERAN, citizens of the United States, residing at Moulton, in the county of Lavaca, 5 State of Texas, have invented certain new and useful Improvements in Water-Levels; and we do hereby declare the following to be a full, clear, and exact description of the invention, such as will enable others skilled in 10 the art to which it appertains to make and use the same.

This invention relates to leveling instruments and it has for its object to provide a construction that may be used for determining a level at widely distant points or in determining inclinations under the same conditions and furthermore to provide an instrument which may be correctly read under such conditions as where it cannot be held in 20 erect position.

Figure 1 is a side elevation of the device, one of the gages being shown in section.

Fig. 2 is a sectional view on line 2—2 of Fig. 1.

Fig. 3 is a sectional view on line 3—3 of Fig. 1.

Fig. 4 is a section on line 4—4 of Fig. 1.

The device comprises a pair of glass gages 1, and since they are identical in construction a description of one will suffice for both.

Each gage comprises a glass tube 2, said tube being connected in a metallic sleeve 3, said sleeve having an elongated sight opening 4 formed therein so that the level of the water in the tube can be readily observed. 35 The upper end of the tube 2 projects slightly above the upper end of the sleeve 3, as does the lower end of the tube project below the lower end of the sleeve.

40 Threaded upon the upper end of the sleeve 3 is a cap 5, said cap having an annular shoulder 6 formed therein, said shoulder serving to engage the packing ring 7 so as to hold the same firmly engaged with the upper 45 end of the tube 2. The packing ring can be compressed as desired since the cap 5 is threaded upon the sleeve.

Carried by the cap 5 is a valve 8, which can be operated to permit air to escape from the tube 2 so as to break the vacuum therein, thus permitting the liquid to rise and fall freely.

46 Threaded upon the lower end of the sleeve 3 is a coupling 9, said coupling having an annular shoulder 10 formed therein for holding the packing ring 11 in tight engagement with the lower end of the tube 2 when the

coupling is secured tightly upon the sleeve. The couplings 9 are provided with reduced extensions 12 which are engaged by the ends of the flexible tube 13, and to hold the ends of the tube engaged on the extensions clamping bands 14 are employed. 60

Since the gages 1 are connected by the tube 13 it is obvious that the same can be moved and that the differences in the height of objects can be readily ascertained. 65

It will be of course understood that graduations are provided so as to designate the differences between the heights of points, and these graduations can be marked upon 70 the tube or upon the sleeve, as desired.

A combined inclinometer and level attachment is provided for one of the gages and consists of a frame 15, said frame having a vertical arm 16 and horizontal arms 17 which are connected with the cap 5 and coupling 9. Fixed centrally of the arm 16 is a block 18, said block serving to support one side of the circular band 19, the other side of which is fixed to the sleeve 3; said band having 80 marked thereon suitable graduations. Also supported by the block 18 is an arm 20 to the inner end of which is pivotally connected a casing 21, said casing having pointed ends 22 which co-act with the graduations so as to 85 indicate the number of degrees between the inclination and the horizontal, said casing having mounted therein a spirit tube 23 which when at right angles to the gage will enable a level to be determined accurately. 90 Since the casing 21 is pivotally mounted it is obvious that the same can be adjusted to any desired angle.

It will be noted that the lower end of the coupling 9 includes a valve casing 24 in 95 which operates a valve 25. Thus it will be seen that the water in this gage can be transferred to the other gage and the valve closed, after which the coupling 9 can be removed from the casing 24 since said coupling is 100 screwed into engagement therewith, as at 26, thereby permitting the attachment to be used separately. After the valve is closed it is obvious that the fluid will be trapped in the tube 13 and the other gage. 105

In one use of the apparatus, the two ends are held side by side and adjusted with respect to each other until the water level in both tubes registers the same on their respective scales. One tube is then held in 110 vertical position with this identical point that has been read on the scale at the known

level. The other end of the apparatus is then manipulated into vertical position until its water level is on the same point of its scale as formerly. Water level in that tube will indicate a point at the same altitude as the known point.

At times, the head room may not permit of the tubes being held vertical in the determination of the second point. Under such circumstances, when the known point is located where head room is limited, the two tubes are put side by side as in the first instance and are held at such inclination as the head room will permit and with the water level in both tubes at the known altitude point. The indication on the scale of the spirit level on one of the tubes is then noted so as to read the inclination of the tubes. The tube having the spirit level is then carried to the remote position and is tilted so that the spirit level scale will read exactly the same as formerly and is further manipulated so that at such inclination of the tube, the water level in that tube will read the same as just previously. The point at which the spirit level will show the same inclination as formerly and with the water level the same as formerly, is the point whose altitude

is the same as the altitude of the known point.

Of course, if the place at which the altitude point is to be determined is the one that lacks head room, the inclination at which the two water gages are to be read, is determined at that place.

What is claimed is:—

The combination with a pair of gages adapted to contain liquid, and a flexible tube connecting the gages of a frame having its ends engaged with one of the gages, an annular member carried by the frame and disposed between the same and the gage and having graduations thereon forming a scale, an arm extending from the annular member toward its center, a pointer pivoted to the arm and having its extremities movable over the scale and a spirit level within the pointer and exposed centrally thereof.

In testimony whereof, we affix our signatures in the presence of two witnesses.

JOHN KASPAR.
RUD F. BERAN.
